COMBINED HELMET AND CAPE

Byron W. Gutheil, Pasadena, Calif.

Application May 2, 1958, Serial No. 50,725

Term of patent 14 years

(Cl. D3—13)

FIG. 1.

FIG. 2.

I claim:

The ornamental design for a combined helmet and cape, as shown.
